UNITED STATES PATENT OFFICE.

GERALD ST. JOHN DAY, OF OLDHAM, ENGLAND.

CONNECTOR.

1,105,889.

Specification of Letters Patent.

Patented Aug. 4, 1914.

Application filed May 20, 1913. Serial No. 768,715.

To all whom it may concern:

Be it known that I, GERALD ST. JOHN DAY, a subject of the King of Great Britain, residing at Oldham, in the county of Lancaster, England, have invented new and useful Improvements in Connectors, of which the following is a specification.

This invention relates to terminal mounting and cord gripping means for electric lamp holders, adapters, or the like, and consists in so combining the terminal, the insulating terminal mount, and the cord or conductor, as to provide an efficient support for the terminal without the use of fixing screws or like attachments, and, at the same time, to grip the cord for the protection of the bare wire connection, without the use of split cones or other separate cord gripping devices.

I provide an insulating block or support for the terminals, which may be more or less recessed to provide adequate seating and lateral support therefor, or, it may be, for pillars or bases suitable for the attachment of the terminals. The said terminals may thus be formed in one with the contact making surface, or attached to contact pieces by suitable means. The block or support is also provided with passages for the wires, leading to the said recesses where such are employed, and the terminals, which have suitable provision for the connection of the bare wires, may be provided with coned or shouldered abutments to fit the seatings, for the better security of the mounting, as well as to assist the cord grip as hereinafter described. The said pillars or terminals are provided with stems or equivalent extensions, which are screw-threaded, roughened, or otherwise adapted to grip, and which are passed into the holes in the block or support along with the cord or conductor. The cord may be first passed through the block, and connected to the terminal, which may then be introduced into the passage, and forced on to its seating by pulling the cord from the outer end. Thus an efficient cord grip is provided by the close conjunction of the parts along the passage. The cord and stem, being in gripping communication, tend to move together, and, consequently, there is little or no strain upon the bare wire connection. Further, the cord, when passed over the seating, is, to some extent trapped by the terminal, and additionally gripped. The passages in the block or support are

preferably narrower at the outer than at the inner end, whether by tapering, stepping down, or otherwise, so as to increase the gripping tendency, and to enable the cord passing out beyond the terminal to more efficiently cover up and insulate the end of the latter. Pulling on the cords, or pressure upon the terminals from a lamp or adapter will tend to increase both the cord grip and the security of the terminal. On the other hand, the terminal may be readily removed from the mount, when required, by simply pulling in the opposite direction, without dismembering the mount or casing.

The accompanying drawings illustrate certain forms of apparatus according to my invention.

Figure 1 shows in section part of a mount or support, with the terminal (partly in section) and cord in position. Fig. 2 shows the same terminal detached, and partly indicated in dotted lines. Fig. 3 is a similar view to Fig. 1, the terminal, and the hole in the mount being slightly modified. Figs. 4, 5, 6, and 9 show various forms of terminal, and Figs. 7 and 8 illustrate, in section, two adaptations of the invention to lamp holders.

In all the views, *a* is the mount, support or block, *b* the terminal as a whole, and *c* the cord.

In Fig. 1 the opening in the block is shouldered at *d* to provide a seating for the body of the terminal, and to trap the cord passing over, which seating may be at the side as shown or otherwise. The stem *e* of said terminal is threaded or roughened to efficiently grip the cord *c*, which is pressed against the same by the sides of the passage in the block *a*. One of these sides is shown slightly tapered toward the outlet. A detachable contact piece or plunger *h* is connected to the terminal by a screw projection on the latter, and the bare wire may be secured between the two parts. A vertical groove *i* is formed in the terminal body to accommodate the cord on its way to the stem. This groove is more clearly illustrated in Fig. 2 which indicates the terminal without the cord and mount, the detachable plunger being shown dotted. Alternatively or additionally the vertical or other groove for the cord may be formed in the mount.

In Fig. 3 no shoulder such as *d* is used, but the passage is symmetrically tapered, and the stem *e* is centrally situated. In this case the plunger is formed in one with the

22
stem, and a nut *h*, engaging the latter, serves to nip the bare wire in place.

In Fig. 4 the screw projection for attaching the contact piece to the terminal body is shown on the plunger portion, reversing the method exemplified in Figs. 1 and 2. In this figure, also, the roughening of the stem *e* is enlarged, and takes the form of gaps *l*, about which the cord may be wound before the stem is inserted into the passage. Fig. 5 is a similar arrangement, with fewer gaps.

Fig. 6 shows the cord passed through holes in the stem, which method is equivalent to the closing in of the gaps *l*. These holes, marked *m*, while providing for the retention of the cord in position on the stem, when the terminal is removed from the block, act in conjunction with the sides of the passage, to efficiently grip the cord as in the former cases.

The terminal bodies in Figs. 4 and 5 are adapted to fit a conical seating.

In Fig. 7 a lamp holder is shown with one of the terminals in position, and the other ready for insertion into the passage of the mount *a*.

Fig. 8 shows a form of lamp holder without metallic casing, the body *a* being in two parts *n* and *o*. The terminals *b* are attached to the former in the manner already described.

Downwardly projecting screws on the terminals pass into shouldered passages in the part *o*. These screws engage the contact pieces *h* which are inserted from below. Screwing up of the engaging parts will draw together the body sections *n*, *o*. This method of forming the body is convenient, but is not claimed as part of my present invention.

It is not essential in all cases for the body of the terminal to enter the passage in the mount. Thus, Fig. 9 illustrates the mounting of a terminal suitable for adapters. The stem only enters the passage, and the head forms the contacting surface. Furthermore, it will be obvious that the terminal need not invariably be formed as presenting a body and a stem, but may be of regular cross section throughout, if preferred.

It will be seen from the foregoing description that, by my invention, the terminal and cord are together brought within a passage in the mount, and that such cord, compressed by the mount and the terminal, retains the

latter securely in position, while being itself efficiently gripped to prevent strain upon the bare wire connection.

Thus a simple, economical, and efficient terminal mount and cord grip is provided, which may be readily assembled or dismembered, and which conduces to better insulation and fewer parts than ordinary.

For screw lamps, one terminal may be mounted as described, while the second wire may be connected to the metallic casing connection in the usual way; or, if desired, the said metallic connection also may be secured according to the invention by means of a projecting stem or the like.

It will be obvious that the invention is applicable to other electrical devices than those named, such as ceiling roses, or plugs.

I claim:—

1. In a terminal and cord mounting device, and in combination, an insulating mount having a restricted passage therein, a conducting wire in said passage having an insulating outer covering in close frictional contact with the wall of said passage, and a contact making terminal electrically connected to said wire, and projecting within said passage, said terminal being independent of direct means of attachment to said mount, and being in close frictional contact with the outer surface of said insulating covering and adapted to grip same, for the purpose and substantially as herein set forth.

2. In a terminal and cord mounting device, and in combination, an insulating mount having a restricted passage therein, a conducting wire in said passage having an insulating outer covering in close frictional contact with the wall of said passage, and a contact making terminal electrically connected to said wire, and having a stem projecting within said passage, said terminal being independent of direct means of attachment to said mount, and said stem being in close frictional contact with the outer surface of said insulating covering, and adapted to grip same, for the purpose and substantially as herein set forth.

In testimony whereof I have signed my name to this specification in the presence of two subscribing witnesses.

GERALD ST. JOHN DAY.
